UNITED STATES PATENT OFFICE.

JOHN DESMOND, OF CHICAGO, ILLINOIS, ASSIGNOR TO WILLIAM S. POTWIN, OF CHICAGO, ILLINOIS.

ELECTRIC SWITCH.

1,118,188.

Specification of Letters Patent. Patented Nov. 24, 1914.

Application filed March 25, 1912. Serial No. 685,941.

To all whom it may concern:

Be it known that I, JOHN DESMOND, a citizen of the United States, residing at Chicago, in the county of Cook and State of Illinois, have invented certain new and useful Improvements in Electric Switches, of which the following is a specification.

My invention relates to automatic electric switches.

10 One of the objects of my invention is to provide a switch adapted to be placed in circuit with an electric motor adapted to be automatically opened upon the occurrence of a rise of pressure within a receptacle and 15 to be automatically closed when the pressure falls below a predetermined value.

In instances where an electric motor is used to operate an air pump to compress air within a receptacle wherein it is desired to 20 maintain the pressure within certain limits while the air therefrom is drawn intermittently, it is of economical advantage to automatically stop the motor when the desired pressure has been reached and to start the 25 motor again when the pressure has fallen below a predetermined value. Such examples are in the use of air operated car brakes; charging tanks for pneumatic tires, and in many other situations that will 30 readily occur to persons skilled in the art.

In the illustrative exemplification; Figure 1 is an elevation, partly in section, showing my switch; Fig. 2, is a vertical, central section taken on line 2—2 of Fig. 1; Fig. 3 35 is a plan view of the device; Fig. 4 is an enlarged air valve detail; Figs. 5 and 6 are details for adjusting the vertical position of the air valve and the extent of its lost motion.

40 In all of the views the same reference characters indicate similar parts.

The base casting 10 is a means whereby the device may be secured to a support. It is centrally bored and screw threaded, as at 45 11, thereby providing an aperture 12. A lateral boss 13, preferably an integral part of the base casting, projects from the central hub 14, at one side of the radial limit of the disk 15. A perforation 16 is enlarged at its outer end and is screw-threaded as at 17 for a pipe 18. The opening 16 permits communication from pipe 18 to the central opening 12. A bottom disk 19 with the top disk 20 provides a diaphragm casting for a diaphragm 21, which is secured

at its edges between said disks and firmly held therein by the screws 23. Each disk is provided with central, axially perforated hubs 22 and 26, respectively; said hubs are exteriorly screw-threaded, as at 24 and 25. 60 The hub 26 is interiorly screw-threaded, as at 27, for valve controlling, axially movable plugs 28 and 29. The plug 28 is screw-threaded, as at 30 and 31, interiorly to permit longitudinal movement of the threaded 65 plug 29 therein and exteriorly for engagement with the screw threads 25 of the hub 26. The plug 28 is split, as at 32, so as to increase the friction between said plug and the screw-threaded aperture in which it is 70 contained, that it may remain undisturbed in the position to which it may be moved.

An air valve stem 33, is provided with a head 34, which is smaller in diameter than the plug 29, and is adapted to pass through 75 the aperture 35 in the plug 28. A shoulder 36 prevents the head 34 from passing through the smaller bore 35. The stem 33 is axially perforated, as at 37, and transversely split, as at 38, to permit air coming 80 through the pipe 18 to enter the space in the diaphragm casing below the diaphragm. The stem 33 is also provided with a transverse bore, as at 39, that intersects the central axial bore 37, and immediately above 85 said transverse bore it is provided with a tapered valve 40. A central stem 41 is secured to the diaphragm 21, as at 42. It is axially bored with perforations of two diameters, as at 43 and 44. The shoulder 90 formed at the juncture of the two bores provides a valve seat for the valve 40. An open compression spring 45, is contained within the hub 22, surrounds the stem 41, and seats on a shoulder at the lower end 95 thereof. It is the means for holding the valve seat of the stem 41 on the valve 40 thereby to shut off communication between the bores 43 and 44. A cap 46 has screw-threaded engagement with the hub 22 for 100 adjusting the tension of the spring 45 upon the diaphragm 21, thereby to vary the pressure at which the switch will operate. The cap is also centrally bored and serves as a guide for the stem 41.

105 From the foregoing description it will be understood that when the air pressure below the diaphragm 21 minimizes the effect of the spring 45, that the stem 41 will be lifted and thereby separates the valve 40 from its seat, 110

permitting air to enter the bore 43, from the source of air supply coming through the pipe 18.

The split, 38, in the stem 33, permits yielding expansion of the stem 33, so that friction between it and its surrounding enclosure in the stem 41 causes the stem 33 to move with the stem 41 until the head 34 strikes the shoulder 36 in the plug 28, when further movement of stem 41 in an upward direction opens the air valve 40. Thus the extent of vertical space between the shoulder 36 and the plug 29, within which the head 34 of the stem 33 has lost motion movement, is the means of varying the difference in pressure at which the electric motor circuit will be closed and opened. A cap 47 is centrally bored and is attached to the stem 41. On its upper end it carries a casting 48, which is axially bored, as at 49 for a piston 50 that moves freely therein.

A casing 51 is secured by screws to lug 52 rising from disk 20. In the upper end of the casing is secured, as by screws 53, a disk 54 of insulating material, such as porcelain or the like, and mounted on said disk are two segment-shaped pieces of carbon 55 and 56 interiorly tapered as at 57, and constituting the stationary terminal electrodes of the switch. Screws 58 and 59 take through the disk 54 and are countersunk in the blocks 55 and 56 respectively, and on their lower threaded ends carry nuts 60 and 61, respectively, by which conducting wires 62 and 63 may be connected. The casing 51 is perforated as at 64 and 65 to admit said wires.

A carbon plug 66 is tapered for contact with the tapered surfaces of the terminals 55 and 56, and when in place, as shown in the drawings, serves to close the electric circuit therebetween. Said plug is mounted on an insulating support 67 and secured thereto by the nut 68. Interior of the insulating support is a metallic cup 69.

A stem 70 carries on its lower end a collar 71 that guides the stem in the hollow piston 50 and serves as an abutment for the open-coiled spring 72, that abuts against the bottom of said hollow piston, and yieldingly holds it in the bottom of the bore 49.

A permanent magnet consisting of the limbs 73 and 74 and a yoke 75, is secured to the casting 48, as by screws 76. A keeper 77 consisting of an iron washer is held in place by nuts 78-79 on the stem 70. The keeper makes contact with the poles of the magnet and is normally held there by said magnet during the time when the switch is closed. When air is admitted under the piston 48, by opening of the valve 40, as when the rise of pressure causes the diaphragm 21 to lift the stem 41 away from the valve end of the stem 33, the piston will be moved upwardly in the bore 49, the first portion 65 of its movement will compress the spring

72, which is not sufficient to overcome the portative effect of the permanent magnet by the operation of the stem 70 and the nut 79 to lift the keeper 77. Further movement of the piston produces actual contact with the bottom end of the stem 70, when the keeper 77 will then be positively moved away from contact with the magnet. As soon as actual contact is broken the spring 72 will then further move the keeper 77 with a quick snap-like movement and with it the plug 66, thereby opening the circuit between the carbon blocks 55 and 56. When the diaphragm 21 moves downwardly, as by the spring 45, as a result of decrease of air pressure, the parts will again assume their respective positions, shown in Fig. 2, and the switch will be again closed and the motor thereby started to increase the pressure. If the stem 33 were rigidly stationary it would require but very little variation in pressure to open and close the valve 40 and the motor would be started and stopped at unnecessarily frequent intervals. To avoid this I provide lost motion movement of the stem 33 by permitting the head 34 thereof to move within the space between the shoulder 36 in the plug 28 and the adjustable plug 29. The greater this space the greater will be the variation of pressure permitted before the switch will be operated.

A spring 80 serves to hold the plug 66 in an elevated position on the rod 70 with reference to the nut 81, so that said plug may be adjusted to position where it will be in contact with the blocks 55 and 56 when the keeper 77 is seated on the magnet. The nut 68 is tapered at its upper edge and springs 82 and 83 carrying rollers 84 and 85 respectively are secured to opposite sides of the casing as at 86 and 87 by screws 53. The rollers bear upon the tapered surface of the nut and serve to press the plug 66 more firmly into contact with the segment electrodes 55 and 56. When the nut 68 is raised, as when the switch is open the rollers ride on the outer parallel surface of the nut and offer very little resistance to means for elevating the plug 66.

While I have herein described a single embodiment of my invention for purposes of complete disclosure, it is evident that departure may be made from the specific showing and within the scope of the appended claims without avoiding same.

What I claim is:

1. In a device of the character described, the combination of a diaphragm, a valve controllable thereby comprising a member movable with the diaphragm and a member with respect to which the diaphragm moves, said second member being mounted to permit lost motion thereof, and means whereby said second member is carried with said diaphragm - moved member in either

- direction to the extent permitted by said lost motion.
2. In a device of the character described, a diaphragm, a valve, and means for control of the latter by the former comprising connections therebetween having parts associated for initial non-effective lost motion upon movement of the diaphragm in either direction, one of said parts being adjustable to vary the extent of said non-effective lost motion of the diaphragm in either direction.
3. In a device of the character described, the combination of a diaphragm, a valve controllable thereby comprising relatively movable seat and valve members, said members having portions frictionally engaging, one thereof carried by the diaphragm and the other having lost-motion connection with a supporting base, and a supporting base for said parts.
4. In a device of the character described, the combination of a diaphragm, said diaphragm having a central perforation, a valve comprising relatively movable seat and valve members, one frictionally engaging within the other, the outer member carried in said central perforation of the diaphragm and the inner projecting through said perforation within said diaphragm-carried member, said inner member being shaped to permit passage of fluid under pressure through said diaphragm-carried member, and means to support said inner member permitting lost-motion for movement thereof with the outer member in either direction.
5. The combination with a diaphragm and diaphragm-carried valve member, of a co-acting valve member provided with a laterally projecting part, a casing member, a plug adjustable in said casing, and a second plug adjustable with respect to the first said plug, said laterally projecting part of the valve member being included between said two adjustable plugs, whereby to provide lost-motion for said valve member the limits of which are adjustable.

In testimony whereof I hereunto set my hand in the presence of two witnesses.

JOHN DESMOND.
